No. 37,257.

Patented December 6, 1904.

UNITED STATES PATENT OFFICE.

WILLIAM H. LLOYD, OF CHICAGO, ILLINOIS, ASSIGNOR TO CRANE COMPANY, OF CHICAGO, ILLINOIS, A CORPORATION OF ILLINOIS.

DESIGN FOR A BATH-TUB.

SPECIFICATION forming part of Design No. 37,257, dated December 6, 1904.

Application filed March 9, 1904. Serial No. 197,365. Term of patent 7 years.

To all whom it may concern:

Be it known that I, WILLIAM H. LLOYD, a citizen of the United States, residing at Chicago, county of Cook, and State of Illinois, 5 have invented a new, original, and ornamental Design for a Bath-Tub, of which the following is a specification, reference being had to the accompanying drawing, forming part hereof. The figure is a perspective view of the bath 10 tub showing my design.

What I claim as new, and desire to secure by Letters Patent, is the ornamental design for a bath tub as shown.

WILLIAM H. LLOYD.
